UNITED STATES PATENT OFFICE

2,511,038

COLLAPSIBLE TUBE CAP

Louis Bergeron, Chicago, Ill.

Application December 5, 1945, Serial No. 632,915

1 Claim. (Cl. 222—517)

1 My invention pertains to interchangeably removable caps used primarily in conjunction with collapsible tubes of standard manufacture, which are utilized in merchandising and holding or retaining of plastic material.

One object of my invention is to provide a cap having body means articulately secured to a closure means, and having interposed between the closure and the body means of the cap, at the point of articulation, resilient means for maintaining the closure in open position and hermetically sealed in closed position.

Another object of my invention is to provide in a novel device of the aforementioned character an articulating hinge element, which serves an additional function of acting as a resilient retaining means, retaining the closure element in a fixed open position and also in a fixed closed position, that is, the resilient retaining means requiring slight effort to be exerted in order to disengage it from the fixed position either when open, or closed whatever the condition happens to be.

Another object of my invention is to provide an article, or device, of the aforementioned character, which may be used interchangeably with collapsible tubes, after the materials have been dispensed therefrom, and a cap which will have all its elements self-retained so as to remove the difficulties at present contended with, through the use of separable or removable caps conventionally associated with collapsible tubes of commercial manufacture and construction.

Another object of my invention is to provide, in a cap of the aforementioned character, dispensing lip means which will serve the function of maintaining the dispensing opening clean and will permit clean wiping of the said lip means after plastic material is dispensed therefrom, thus preventing contamination of the material confined within the cap, presenting at all times a neat appearance, rather than the messy unsightly appearance that is prevalent where removable caps are utilized.

Another object of my invention is to provide an article of the aforementioned character which is simple in construction, contains few parts, requires few operations for its manufacture and construction, and which is practical and efficient for the purposes intended, being also of such elemental assemblage and construction as to warrant economical manufacture thereof in quantity production.

Other features and advantages resident in my invention, will become apparent from an ex-

amination of the accompanying drawings, further elucidated in the ensuing description, so that those familiar with the art will have no difficulty in grasping the teachings expounded herein; the said drawings indicated in the various figures or views, wherein like numerals, or symbols, are used to designate like parts; and, in which,

Fig. 1 is a perspective view of a collapsible container with my invention attached thereto, showing the particular application when the collapsible container is filled with tooth paste, and showing a toothbrush removing some of the material from the tube, "clean-wiping" the same.

Fig. 2 is a front view of my invention, with certain portions thereof, shown in section in order to more clearly elucidate the construction thereof.

Fig. 3 is a view similar to Fig. 2 with the exception that the closure portion of my invention is shown in open position ready for use.

Fig. 4 is a fragmentary sectional view taken, substantially, on the line 4—4 of Fig. 2.

Fig. 5 is a perspective view of an important element used in connection with my invention.

Referring to the various views my invention is, generally, designated 6, and it is attached to the threaded mouth 10 of a collapsible tube 9, the materials being dispensed through the elevated lip portion 15, so that a brush 7 having its bristles 8 drawn across the said lip 15 will remove all of the material ejected from the tube when the same is compressed, yet leaving the neck at the end of the opening 14 clean at all times, and free from contamination by foreign matter prevalent in the atmosphere.

My invention, generally, designated 6 consists of a body member 11, having a female threaded portion 12 mating with the threaded portion on the neck 10 of a collapsible tube 9, being further provided with a ledge extending to one side thereof of which terminates in two ears 20 forming part of an articulate assembling arrangement, the other ears 21 being on the closure element 18 so as to receive the hinge element shown in Fig. 5.

The said hinge element consists of hinge portions 23 which have adjacent or contiguous thereto the flat portions 24 and the intermediate portions 25, which are bent at the center to form the duplex hump portion 26, having indentations 27 and 28 and being bent at 29, making the entire affair from one piece of wire.

The purpose of the flat portions 24 is to permit them to be securely anchored in the ears 20. The ears 21 are rotatably secured to the intermediate portions 25. In between the ears a U-shaped re-

cess 22 is provided, having a sharp central edge as indicated in Figs. 2 and 3, and the said edge 22 engages either the formation or indentation 27 or 28.

In Fig. 2, when engaging the indentation 22, the closure 18 is closed, thus confining sealably the edge 17 thereof with the top surface 16 of the body 11. The closure 18 is provided with an enlarged conical recess 19 in order to provide sufficient and ample clearance for the lip structure 13. The material is ejected through the bore 14 which merges with the enlarged threaded portion 12 of the body 11 so that whenever the cap 9 is squeezed or pressed it causes the plastic material contained therein to be ejected therefrom.

The terminus central portion 29 of the wire portion 26 is caused to slidably and frictionally engage the lower surface 30 of the ledge component portion connecting the ears 20 to the body 11. The reason for that is, in order to afford a resilient action to the spring hinge, or to the resilient hinge structure 26, inasmuch as the flat portion 24 being securely anchored, the snapping engagement of the hinge 22 with either indentation 27 or 28 will offer a yieldable pressure and resistance, to be overcome readily by a slight pressure to be exerted on the closure 18 whenever it is desired to open the cap or close the cap, causing either engagement of the edge 22 with the indentation 27, or engagement with the indentation 28, or disengagement with any of the said indentations 27 or 28 respectively. The operation and use of my invention is believed readily obvious and self-evident from the foregoing description.

Although I have herein described and revealed rather succinctly the construction of my invention, and inasmuch as the same is susceptible of modifications and improvements, I hereby reserve the right to all modifications and improvements coming within the scope and spirit of my

invention, also those modifications and improvements embraced impliedly in the accompanying drawings, as well as all those falling within the purview of the foregoing description.

Having thus described and revealed my invention, what I claim as novel, and desire to secure by Letters Patent, is:

A collapsible tube cap of the character described comprising, a body element provided with a threaded portion removably engaging the neck portion of a collapsible tube and further provided with an extended hinge portion, a closure element having a mating hinge portion articulately secured to the said extended hinge portion and further provided with an open slotted portion at its lower edge providing a locking edge portion intermediate said mating hinge portion, and a pivot element anchorably secured to one of the said hinge portions and freely operative in the other of said hinge portions, the said pivot element being provided with a central hump portion having its free terminus in intimate contact with the lower surface of the said extended hinge portion and having two indentations adapted to engage releasably the said locking edge portion in snap relationship in both open and closed positions of the said closure element.
